UNITED STATES PATENT OFFICE.

DAVID RENSHAW, OF COHASSET, ASSIGNOR OF ONE-HALF TO DREW & COFFIN, OF BOSTON, MASSACHUSETTS.

STEAM-GENERATOR.

SPECIFICATION forming part of Letters Patent No. 237,408, dated February 8, 1881.

Application filed February 20, 1880.

To all whom it may concern:

Be it known that I, DAVID RENSHAW, of Cohasset, in the county of Norfolk and State of Massachusetts, have invented a new and useful Steam-Generator, of which the following is a specification.

The object of my invention is the production of a sectional steam-generator which will occupy little vertical space, will break up and slow the water as it rises from bottom to top, will circulate the water freely, and which is capable of being made long or short, as the necessities for its use may require, and it is an improvement on the boiler patented to me August 3, 1880, and numbered 230,818. For this purpose I construct each section of my generator with a small lower pipe, A, and large upper pipe, B, parallel to one another and horizontal, the said pipes being connected by curved tapering pipes C, so that the pipes A, B, and C form one unbroken continuous pipe. From the lower pipe, A, within the space enclosed by the pipes A, B, and C, vertical pipes D rise a short distance and connect with semicircular pipes, D', said pipes D' having each two openings into the pipe B, and both D and D' having the same diameter.

In the drawings, Figure 1 shows a partial section through the generator, showing one section in front elevation; and Fig. 2 shows a section in side elevation.

The water in the pipe A, when heated, rises rapidly through the pipes D and strikes against the lower portion of the semicircular pipe D', by which action it is broken up effectually for the disengagement of steam, expanded and passed to the upper pipe, B, through two branches, D' D', each of the diameter of pipe D, entering said pipe B through two openings, each of the size of the outlet from the pipe A. This construction, in addition to the breaking up of the water passing through D by its con-

tact with the bottom of D', slows the current and delivers the water to pipe B with much less velocity and with less derangement of the water-surface in B than would be attained if the pipe D had only one connection with pipe B. The water thus thrown into pipe B will, after its steam is disengaged, return by means of the pipes C to the lower pipe, A, to be again forced through the pipes D and D', broken up and expanded as before, said arrangement and construction of the pipes affording a complete circulation of the water, and its consequent evaporation.

I have shown in the drawings but two series of the pipes D D', and this would be all that would be requisite for a small boiler; but it is evident (and one of the features of my invention) that the pipes A and B may be prolonged, and three, four, or many more such series be connected with them, so that the sections may be placed endwise to the front of the boiler and extended any desired distance beyond the fire, several of them being arranged side by side, and this, in connection with the short distance between the bottom of the pipe A and the top of the pipe B, would make the boiler available for many purposes. The sections are connected together by feed-pipes E and steam-drum G in an ordinary manner.

What I claim as my invention, and desire to secure by Letters Patent, is—

The section of a boiler composed of a small lower horizontal pipe, A, and large upper horizontal pipe, B, connected at their ends by curved tapering pipes C, said pipes A and B being further connected by short vertical pipes D engaging with semicircular pipes D', all as described, and for the purpose specified. DAVID RENSHAW.
